Des. 224,868
Patented Oct. 3, 1972

224,868

MOBILE COCKTAIL BAR

Vincent J. Intorcio, 7123 Mentor Ave.,
Mentor, Ohio 44094

Filed Sept. 14, 1970, Ser. No. 24,991

Term of patent 14 years

Int. Cl. D6—03

U.S. Cl. D6—144

Fig. 1

Fig. 3

Fig. 2

Fig. 4

Fig. 5

FIG. 1 is a front view of a mobile cocktail bar, embodying my new design;

FIG. 2 is a back view of the same;

FIG. 3 is a right-end view of the same;

FIG. 4 is a left-end view thereof; and,

FIG. 5 is a top-plan view of the same.

I claim:

The ornamental design for a mobile cocktail bar, substantially as shown.
